(57) **CLAIM**

The ornamental design for a multimedia distribution package, as shown and described.

DESCRIPTION

FIG. 1 is an outside view, shown in perspective, of a multimedia distribution package according to the present invention;

FIG. 2 is a top plan view of the multimedia distribution package shown in FIG. 1;
FIG. 3 is a bottom plan view of the multimedia distribution package shown in FIG. 1;
FIG. 4 is a right side elevation view of the multimedia distribution package shown in FIG. 1;
FIG. 5 is a left side elevation view of the multimedia distribution package shown in FIG. 1;
FIG. 6 is a front elevation view of the multimedia distribution package shown in FIG. 1;
FIG. 7 is a back elevation view of the multimedia distribution package shown in FIG. 1;
FIG. 8 is a perspective view of a bottom portion of the multimedia distribution package shown in FIG. 1, with a top portion of the multimedia distribution package having been removed to display the computer software and documentation held in place by a packaging insert;
FIG. 9 is a top plan view of the multimedia distribution package shown in FIG. 8;
FIG. 10 is a bottom plan view of the multimedia distribution package shown in FIG. 8;
FIG. 11 is a right side elevation view of the multimedia distribution package shown in FIG. 8;
FIG. 12 is a left side elevation view of the multimedia distribution package shown in FIG. 8;
FIG. 13 is a front elevation view of the multimedia distribution package shown in FIG. 8;
FIG. 14 is a back elevation view of the multimedia distribution package shown in FIG. 8;
FIG. 15 is an enlarged perspective view of the packaging insert shown in FIGS. 8 and 9, the packaging insert as being shown separately in FIGS. 15–21 for clarity of illustration.
FIG. 16 is a top plan view of the packaging insert shown in FIG. 15;
FIG. 17 is a bottom plan view of the packaging insert shown in FIG. 15;
FIG. 18 is a right side elevation view of the packaging insert shown in FIG. 15;
FIG. 19 is a left side elevation view of the packaging insert shown in FIG. 15;
FIG. 20 is a front elevation view of the packaging insert shown in FIG. 15; and,
FIG. 21 is a back elevation view of the packaging insert shown in FIG. 15.
The broken line showing of environment is for illustrative purposes only and forms no part of the claimed design.
